REEL OR SPOOL

Frank Mossberg and Brox A. Johnson, Attleboro,
Mass., assignors to Mossberg Pressed Steel
Corporation, a corporation of Massachusetts

Application January 25, 1935, Serial No. 3,459

9 Claims. (Cl. 242—123)

This invention relates to a reel or spool; and has for one of its objects the provision of a seamless juncture at the usual right angular corner between the barrel and the head.

Another object of the invention is the provision of a reel or spool having head and barrel portions and in which small wires will not become caught when wound on the reel.

Another object of the invention is the reinforcement of the head and at the same time providing a central tube supporting part.

With these and other objects in view, the invention consists of certain novel features of construction, as will be more fully described, and particularly pointed out in the appended claims.

In the accompanying drawing:

Fig. 1 is an end view of the reel or spool;

Fig. 2 is a side elevation partly in section;

Fig. 3 is a fragmental section on a larger scale than that shown in Figure 2; and on line 3—3 of Figure 1.

Fig. 4 is a fragmental sectional view illustrating a modification;

Fig. 5 is a fragmental sectional view illustrating a different modification;

Fig. 6 is a fragmental sectional view illustrating a still different modification;

Fig. 7 is a fragmental sectional view illustrating a still different modification and showing;

Fig. 8 is a fragmental sectional view illustrating a still different modification.

In the use of reels or spools, particularly where wires of small diameters are wound thereon, it is desirable that there be no seam or joint in which any small wire can lodge and be jammed; and in order that this may be avoided, we have provided an opening in the head and turned inwardly about this opening a flange which has a diameter on its outer surface of substantially that of the diameter of the barrel of the reel or spool. We have then deflected the stock of one of the meeting edges of the flange or barrel or in some way reduced its thickness or the thickness of both of the meeting edges so that they will fit one over the other in a telescoping relation. These parts are then welded, which weld will fill up the seam or any recess at the joint between the two so as to provide a smooth outer surface from the head along the barrel with no joint at the bend or rounded generally right angular relation of the parts; and the following is a more detailed description of the present embodiment of this invention, illustrating the preferred means by which these advantageous results may be accomplished:

With reference to the drawing, 10 designates:

the barrel or body of the spool or reel which is of tubular stock or formed of sheet stock bent into cylindrical shape with its opposite edges secured together by welding. The heads are designated generally 11 and are of identical construction. 5 Each consists of a circular disc 12 stiffened at its periphery by rolling as at 13 outwardly so as to leave a smooth inner surface 14. The head is provided with an opening 15 centrally thereof and the stock about this opening is turned inwardly 10 to provide a flange 16 of such a size that its outer surface 17 will be substantially of the same diameter as the outer diameter of the barrel or body 10. This flange extends at right angles to the head and is rounded at the juncture, as illustrated 15 in the drawing, so that no seam or joint is formed at its generally right angular formation.

At a point spaced from the juncture of the right angular portions, the marginal edge 18 of the flange is deflected as at 19 to provide a step so 20 that the edge 18 and the stock thereabout will be of a smaller diameter than that of the portion 16 of the flange adjacent the head. The extension of this step inwardly will be substantially the thickness of the end of the stock 20 of the body 10 25 so that the edge or end of this body will slide over this inwardly stepped part, as illustrated in Figures 2, 3 and 4, in a telescoping fashion and will there be secured in the telescoped overlapping relation by welding. The weld 21 also fills the 30 space between the end of the body 10 and the step 19 so as to form a smooth outer surface with the surface 16 of the barrel. In this manner no seam or joint is formed in this spool or reel, at the right angular juncture of the head and the 35 barrel as is usual, and wires or threads of small diameters will therefore not wedge or catch in any part of the structure.

In Figures 2, 3, and 4 we have illustrated the edge of the flange as being deflected inwardly to 40 form the step at 19. In some cases, however, as in Figure 5, the marginal edge 23 at the end of the barrel 10, is deflected inwardly to form the step and the welding material 24 is filled in between the end of the flange and the deflected portion 25 which forms the step. In other cases, as is shown in Figure 6, the end of the barrel 10 has been machined out as illustrated at 26 so as to receive the end of the flange, and in still other cases, as shown in Figure 7, both the end of the 45 flange 27 and the end of the barrel at 28 may be machined so that one will overlap the other, which will be the case where both are of the same thickness and machining is to be done; while in Figure 8, we have shown a still different form of

providing a step support which is that of utilizing a reinforcing plate of the head which will be described.

In order that the disc 12 may be reinforced and at the same time provide a support for the central tubular member designated 30, we have provided as a part of the head unit a plate 31 which is welded to the outer surface of the head portion 12 as at 34 and 35 to in some cases span the opening 15 therein. This plate is suitably provided with holes 32, while ears 33 are sheared from the stock thereof so as to engage the shoulder or inner surface of the flange 16 and centralize the plate with reference to the other part of the head. 10 This plate is provided with an opening and inwardly turned flange 36 to receive the central tubular member 30 which is welded thereto as at 37.

As shown in Figure 4, in some instances instead 20 of having the reinforcing plate of the head unit lapping over the outer surface of the head portion 12, the plate 40 may be set into the opening 15 to engage the shoulder at or about the beginning of the flange. While this plate is deflected outwardly as at 41 and provided with an opening 25 to receive the barrel member 30 with its edge rolled inwardly to provide a short flange 42 about the opening to be welded as at 43.

In another case, as shown in Figure 8, the 30 supporting plate 45 of the head unit is cupped inwardly as at 46 to in effect provide two plies for a portion of the head unit and its flange with the inner flange 46 extending beyond the outer flange 47 of the head unit and thus provides with this flange a step as at 48 to receive the end of the barrel thereover without a seam or joint at the right angular juncture of the parts in either the outer or inner flange of the head. In this formation of Fig. 8 the portion 49 of this 35 inwardly drawn plate supports the tube 30 in some desired manner, such as above described. The parts of the head unit are welded together and then the head to the barrel in all forms.

The foregoing description is directed towards 40 the method and construction illustrated, but we desire it to be understood that we reserve the privilege of resorting to all the equivalent changes to which the construction and method are susceptible, the invention being defined and limited 45 only by the terms of the appended claims.

We claim:

1. A reel or spool comprising a sheet metal barrel, a circular head having a central opening with an annular flange about said opening 50 formed from the stock of said head, said flange having an outer diameter adjacent said head substantially equal to that of the outer diameter of the barrel and of a relatively small axial extent compared to said barrel, the end portions of 55 said barrel and flange being in adjacency with one of said end portions being of smaller diameter than the other and with the other end portion extending thereover, and welding material to secure said overlapping parts together at the junction of the outer surfaces of said overlapping parts.

2. A reel or spool comprising a sheet metal barrel, a circular head having a central opening with an annular flange formed about said opening from the stock of the head, said flange having a diameter adjacent said head substantially equal to that of the barrel and of a relatively 60 small axial extent compared to said barrel, the end portions of said barrel and flange being in adjacency with one of said end portions being

reduced in diameter providing a shoulder, the other end portion extending over the reduced portion with its end spaced from said shoulder, and welding material between said shoulder and end to secure said overlapping parts together and 65 fill the space.

3. A reel or spool comprising a sheet metal barrel, a circular head having a central opening with an annular flange formed about said opening from the stock of the head, said flange having a diameter adjacent said head substantially equal to that of the barrel and of a relatively 70 small axial extent compared to said barrel, the edge portion of said flange being reduced in diameter with the end portion of the barrel extending thereover, and welding material to secure said parts in overlapping relation and fill any cavities in the outer surface at the junction of the edge of the barrel and the shoulder on the flange formed by the reduced portion.

20

4. A reel or spool comprising a sheet metal barrel, a circular head having a central opening with an integral flange, means for securing said flange to said barrel, a reinforcing plate spanning said opening and having inward projections 25 raised on the inner surface thereof to extend into said opening and engage the walls thereof to center the plate with reference to said head.

5. A reel or spool comprising a sheet metal barrel, a circular head having a central opening 30 with an integral flange, means for securing said flange to said barrel, a reinforcing plate spanning said opening and having inward projections raised on the inner surface thereof to extend into said opening and engage the walls thereof to 35 center the plate with reference to said head, said plate being itself provided with a central opening in which a tubular member is mounted.

6. A reel or spool comprising a sheet metal barrel, a circular head having a central opening, 40 a flange about said opening integral with said head, the edges of said barrel and flange being in adjacency, one of said edges being reduced in diameter sufficiently to permit the other edge to extend thereover, and welding material to 45 secure said overlapping parts together, a reinforcing plate spanning said opening and having inward projections raised on the inner surface thereof to extend into said opening and engage the walls thereof to center the plate with reference to said head.

50

7. A reel or spool comprising a sheet metal barrel, a circular head having a central opening, a flange about said opening integral with said head, the edges of said barrel and flange being 55 in adjacency, one of said edges being reduced in diameter sufficiently to permit the other edge to extend thereover, and welding material to secure said overlapping parts together, a reinforcing plate spanning said opening and having inward 60 projections raised on the inner surface thereof to extend into said opening and engage the walls thereof to center the plate with reference to said head, said plate being itself provided with a central opening in which a tubular member is 65 mounted.

8. A reel or spool comprising a sheet metal barrel, a circular head unit at the end thereof having an annular flange formed from the stock of said head unit, said flange having an outer 70 diameter adjacent said head substantially equal to the outer diameter of the barrel and of a relatively small axial extent compared to said barrel, and an annular centering portion also formed from the stock of said head unit to extend

within the end of the barrel that this end of the barrel may overlap said annular portion to center the barrel, said overlapping parts being held together in fixed relation by welding.

9. A reel or spool comprising a sheet metal barrel, a circular head unit having a central opening with the portion about said opening formed of two plies, one of said plies having an annular flange about said opening formed from the stock of said ply, said flange having an outer diameter equal to the outer diameter of the barrel and of a relatively small axial extent com-

pared to said barrel, the end portions of said barrel and flange being in substantially abutting relation, the other ply having an annular flange formed from the stock of the other ply of said head unit and within and reinforcing the first said flange and extending inwardly beyond the first said flange and within the end portion of said barrel whereby said barrel overlaps said reinforcing flange, said plies and overlapping parts being held together in fixed relation by welding.
